CLAIM

The ornamental design for a rack for a wall-mounted telephone, as shown and described.

DESCRIPTION

FIG. 1 is a perspective view of a rack for wall mounted telephone, showing my new design, the telephone, calendar, pad and digital numerals being shown in broken lines for illustrative purposes only;

FIG. 2 is a front elevational view thereof;

FIG. 3 is a side elevational view taken from the left of FIG. 1;

FIG. 4 is a rear elevational view thereof;

FIG. 5 is a side elevational view taken from the right of FIG. 1;

FIG. 6 is a top plan view thereof;

FIG. 7 is a bottom plan view thereof.

FIG. 1

FIG. 2

FIG. 3

FIG. 4

FIG. 5

FIG. 6

FIG. 7
